No. 37,415.

Patented April 25, 1905.

UNITED STATES PATENT OFFICE.

ABRAM ALLAN HENDRICKSON, OF ST. ALBANS, NEW YORK.

DESIGN FOR A BASE-BALL-REGISTER BADGE.

SPECIFICATION forming part of Design No. 37,415, dated April 25, 1905.

Application filed March 6, 1905. Serial No. 248,766. Term of patent 7 years.

To all whom it may concern:

Be it known that I, ABRAM ALLAN HENDRICKSON, a citizen of the United States, residing at St. Albans, in the county of Queens and State of New York, have invented a new, original, and ornamental Design for a Base-Ball-Register Badge, of which the following is a specification, reference being had to the accompanying drawing, forming part thereof.

The figure is a plan view of a base-ball-register badge, showing my new design. 10

I claim—

The ornamental design for a base-ball-register badge, as shown.

ABRAM ALLAN HENDRICKSON.
